UNITED STATES PATENT OFFICE.

ROBERT V. BINGAY, OF PITTSBURGH, PENNSYLVANIA, ASSIGNOR TO PITTSBURGH TRANSFORMER COMPANY, A CORPORATION OF PENNSYLVANIA.

DESIGN FOR A CASING FOR TRANSFORMERS.

57,106.

Specification for Design. Patented Feb. 22, 1921.

Application filed May 29, 1920. Serial No. 865,368. Term of patent 14 years.

To all whom it may concern:

Be it known that I, ROBERT V. BINGAY, a citizen of the United States, residing at Pittsburgh, in the county of Allegheny and State of Pennsylvania, have invented a new, original and ornamental Design for a Casing for Transformers, of which the following is a specification, reference being had to the accompanying drawings, forming part thereof.

The design is shown in the accompanying drawings, in which—

Figure 1 is a plan view; and

Fig. 2 is a view in elevation of the transformer.

I claim:

The ornamental design for a casing for transformers as shown.

ROBERT V. BINGAY.
